UNITED STATES PATENT OFFICE

149,858

DESIGN FOR A COLLAPSIBLE GARMENT HANGER

Henry C. Brown, New York, N. Y.

Application June 12, 1946, Serial No. 130,644

Term of patent 3½ years

(Cl. D80—8)

To all whom it may concern:

Be it known that I, Henry C. Brown, a citizen of the United States, residing at New York, in the county of New York and State of New York, have invented a new, original, and ornamental Design for a Collapsible Garment Hanger, of which the following is a specification, reference being had to the accompanying drawing, forming part thereof, in which Figure 1 is a front view of a collapsible garment hanger, showing my new design; Figure 2 is a side view; and Figure 3 is a sectional view on the line 3—3 of Figure 1.

I claim:

The ornamental design for a collapsible garment hanger, as shown.

HENRY C. BROWN.
